LUBRICATING MEANS FOR SEWING MACHINES

Sydney Zonis, Bridgeport, Conn., assignor to The Singer Manufacturing Company, Elizabeth, N. J., a corporation of New Jersey

Application September 9, 1937, Serial No. 162,988

24 Claims. (Cl. 112—256)

This invention relates to loop-taker mechanisms of sewing machines and has for its primary object to provide improved means for insuring proper lubrication of the thread-carrier raceways of sewing machine loop-takers, regardless of the speed of operation of the sewing machine.

A further object of the invention is to provide lubricating means of the above noted character which is designed to avoid excess lubrication of the thread-carrier raceway of a sewing machine loop-taker when the machine is not in operation, and which lubricating means is automatically rendered effective upon operation of the machine.

Other and more specific objects of the invention will be apparent from the following description and claims.

The present invention is based upon the well known expedient disclosed, for example, in U. S. patents to J. P. Weis, No. 1,348,527, Aug. 3, 1920, and to A. H. De Voe, No. 1,940,399, Dec. 19, 1933, of supplying oil to bearing surfaces by introducing the oil into a hollow shaft endwise of said shaft, the shaft serving as an oil conductor, a preferred embodiment of the invention consisting in improved means for supplying lubricant to a hollow loop-taken shaft for lubricating the thread-carrier raceway of the loop-taker, as hereinafter described in connection with the accompanying drawings, in which:

Fig. 1 represents a sewing machine, shown partly in vertical section and partly in front elevation, containing the improved lubricating means for the loop-taker of the sewing machine. Fig. 2 represents a bottom plan view of the machine, with the bottom plate of the lubricant-chamber or gear-casing removed. Fig. 3 represents an enlarged transverse section of the lubricant-chamber disposed below the machine bed-plate. Fig. 4 represents an enlarged detail view in perspective and partly in section, of the device for directing lubricant into the bore of the loop-taker shaft. Fig. 5 represents an enlarged detail perspective view of the baffle-member functioning to intercept lubricant agitated by the loop-taker driving means. Fig. 6 represents an enlarged perspective view of the lubricant-delivery end of the gear-casing plug. Fig. 7 is a detail section of a wall of the gear-casing and illustrates the overflow aperture limiting the depth of lubricant in the casing-chamber.

The sewing machine illustrated in the accompanying drawings has a bed- or cloth-plate 1, from one end of which rises the standard 2 of a hollow bracket-arm 3 overhanging the cloth-plate and terminating at its free end in a head 4.

Rotatably journaled in the bracket-arm 3 is a horizontally-disposed main actuating shaft 5, carrying at one end a belt-pulley 6 and at its opposite end a crank-disk 7. The crank-disk 7 is connected by a link 8 to a needle-bar 9, journaled

for vertical reciprocation in the bracket-arm head 4 and carrying at its lower end a needle 10.

Cooperating with the needle 10 below the cloth-plate 1, in the formation of lock-stitches, is a rotary loop-taker 11 which, in the present instance, performs two rotations for each reciprocation of the needle. The loop-taker 11 is constructed substantially in accordance with that fully described in the U. S. patent to C. A. Kessler, No. 2,085,699, June 29, 1937, said loop-taker having the usual cup-shaped body provided with a loop-seizing beak 12 and with an annular raceway 13. Journaled in the raceway 13 is a thread-carrier 14 restrained, in any usual or suitable manner, against rotation with the loop-taker, and it is the primary object of the present invention to provide means for insuring proper lubrication of said raceway 13. As is well understood by those skilled in the art, the lubricant must be supplied to the raceway so sparingly as not to soil the sewing threads and yet it must be adequate to prevent frictional overheating and undue wear of the parts at high speeds of operation of the machine.

The loop-taker 11 has an axially apertured hub 15 connected, by a wick-filled radial duct 16 in the body of the loop-taker, with a wick-filled duct 17 opening into the raceway 13. The hub 15 of the loop-taker is secured by screws, as 18, upon one end of a rotary loop-taker shaft 19 provided with a bore 20 extending throughout the length of said shaft. The end of the shaft 19 within the loop-taker hub 15 is spaced slightly from the inner wall of the loop-taker body to provide a cavity in which one end of the radial duct 16 terminates. A wick 21 is preferably provided within the shaft-bore 20 to conduct the lubricant through said bore.

The loop-taker shaft 19 is journaled in a horizontally apertured and elongated bearing-bushing 22 secured by a screw 23 in a suitably apertured boss 24 forming an outward extension of one wall 25 of a gear-casing 26. The gear-casing 26 depends from and is preferably integral with the cloth-plate 1 and bearing-bushing 22 extends into the chamber or reservoir 27 provided within said gear-casing. The bottom of the gear-casing is closed by a removable plate 28 secured by screws, as 29, to the side walls of said casing, a gasket 30 being preferably employed to seal the joint.

At its end within the gear-casing chamber 27, the loop-taker shaft 19 carries a spur-gear 31 which is one half the size of and is disposed vertically above a spur-gear 32 in driving engagement therewith. Within the chamber 27, the driving spur-gear 32 is secured by a screw 33 upon the end of an actuating shaft 34, journaled horizontally in a bearing-bushing 35 secured by a screw 36 in the wall 37 of the gear-casing 26 opposite to the wall 25 thereof. Like the wall 60

25 of the gear-casing, the wall 37 thereof also has a boss 38 extending outwardly therefrom to provide a firm support for the bushing 35. The bearing-bushing 35 extends into the gear-casing chamber 27 and has a reduced inner end loosely embraced by an annular flange 32' of the spur-gear 32. The rim of the flange 32' abuts an annular shoulder 35' formed by reducing the end of the bushing, said flange functioning as an oil-guard minimizing leakage of oil along the shaft-bearing aperture of the bushing. The flange 32' also provides for withdrawal, for repair or other purposes, of the shaft 34 without destroying the timing of the loop-taker, because the gears 31 and 32 remain in mesh when said shaft 34 is withdrawn.

The actuating shaft 34 preferably has its axis of rotation in a vertical plane containing the axes of rotation of the loop-taker shaft 19 and the main-shaft 5. The actuating shaft 34 is also journaled in a ball-bearing 39 disposed in a suitably apertured lug 40 depending from the cloth-plate 1 below the bracket-arm standard 2. Adjacent the ball-bearing 39, the shaft 34 carries a peripherally grooved belt-pulley 41, connected by a clip-belt 42 with a similar pulley 43 carried by the main shaft 5, the shafts 5 and 34 rotating in one-to-one relationship.

In order to supply lubricant to the chamber or reservoir 27 of the gear-casing 26 from above the cloth-plate 1, the latter is provided with a vertical filling aperture 44 extending downwardly through the gear-casing wall 25 and preferably to the bottom of said wall. The aperture 44 is preferably provided with a suitably apertured cap 44'. The loop-taker shaft bushing 22 intersects the aperture 44 and is circumferentially provided with a groove 45 located to permit lubricant to flow past said bushing 22. The gear-casing wall 25 is provided, at the lower end thereof, with a slot 46 connecting the filling aperture 44 with the chamber 27. The depth of the lubricant-supply within the chamber 27 is limited by the provision in the boss 24 of an overflow duct 47 leading outwardly from the filling aperture 44 adjacent the bottom end thereof, whereby the teeth of the lower or driving spur-gear 32 dip into the lubricant supply below the hub of said spur-gear and therefore function as lubricant-impelling means. The duct 47 also serves as an air-vent for the chamber 27 of the gear-casing.

Upon operation of the sewing machine, the spur-gear 32, housed by the casing 26, violently agitates the lubricant-supply located in the bottom of the chamber 27, thereby lubricating the intermeshing gears 31, 32, and also the casing-bearings for the shafts 19 and 34. In order to minimize the discharge of excess lubricant at the loop-taker end of the shaft 19, the bearing-bushing 22 is preferably provided with a drain-duct 48 adjacent the outer side face of the lug 24.

In the present case, the lubricant-impelling expedient above described also serves to supply lubricant to the loop-taker raceway 43. The lubricant agitated by the spur-gear 32 is impelled above the driven spur-gear 31 in a direction corresponding to the direction of rotation of said driven spur-gear. This is facilitated by rounding the top wall of the chamber 27. The portion of the cloth-plate 1 forming the top wall of the chamber is preferably provided with a suitably shouldered aperture closed by a transparent, flanged insert 49, of material such as lucite, glass, or the like, thereby providing means for readily

observing the presence of an adequate supply of lubricant in the chamber 27.

In order to deliver the proper quantity of lubricant to the bore 20 of the loop-taker shaft 19, there is provided a tubular baffle-member 50 partly cut away to present a concave face 50' in opposition to the movement of the lubricant, thereby to intercept particles thereof. The baffle-member 50 is disposed between the cloth-plate insert 49 and the spur-gear 31, in close proximity thereto, and extends horizontally from a support comprising a fixed collar 51 provided with an aperture 52 in which the tubular portion of the baffle-member is suitably secured. The collar 51 is secured by a screw 53 upon a reduced portion 54' of a supporting member 54 extending into the gear-casing chamber 27. In the present case, the supporting member 54 comprises a plug secured by a screw (not shown) in a horizontal aperture 55 provided in the gear-casing lug 38.

The tubular portion of the baffle-member 50 has at the bottom thereof an aperture 56 opening into a vertical lubricant-receiving duct 57 in the collar 51. A restricted duct 58 in the reduced portion 54' of the supporting-member 54 connects the duct 57 with a substantially horizontal aperture 59 provided in said reduced portion 54'.

As is illustrated more particularly in Fig. 6 of the drawings, the reduced portion 54' of the supporting-member 54 has a further reduced extension 60 of inverted semi-cylindrical form, projecting freely into the loop-taker shaft-bore 20. The downwardly facing concave opening 61 defined by the extension 60 is in alignment with the aperture 59 above described, whereby said extension 60 constitutes an overhanging wall connecting the aperture 59 and the shaft-bore 20. The end face of the portion 54' of the supporting member 54 is cut away below the extension 60 thereby to provide a lubricant-drainage and pressure-relieving recess 62 between the delivery-aperture 59 and the shaft-bore 20.

When the sewing machine is in operation, the lubricant impelled by the gears within the gear-casing chamber 27 strikes the concave face of the baffle-member 50 with sufficient force to cause particles of the lubricant to enter the duct 57, pass through the duct 58 and aperture 59, across the control-recess 62, and into the shaft-bore 20 endwise thereof. The extension 60 overhanging the drainage-recess 62 constitutes a connecting-guard insuring that lubricant enters the shaft-bore 20, in spite of the centrifugal action of the rotating-gear 31 adjacent the recess 62. However, excess lubricant delivered to the shaft-bore 20 may escape therefrom through said control-recess 62. Furthermore, when the machine is idle, the lubricant remaining in the ducts 57, 58 and in the aperture 59 will drain through the control-recess 62 into the chamber 27, instead of passing into the shaft-bore 20.

It will be observed that the quantity of lubricant delivered to the loop-taker shaft-bore 20 is also to some extent controlled by the delivering capacity of the restricted duct 58 in the supporting member 54. It will be understood, however, that there will be differences in the pressure of the lubricant at different speeds of operation of the machine, thereby in a sense compensating for variations in the quantity of lubricant drawn from the shaft-bore under the centrifugal action of the loop-taker at different speeds of operation.

It will be noted from the foregoing description that no lubricant will be supplied to the loop-taker shaft bore when the machine is idle, a con-

dition which is obtained automatically and obviates any necessity of initially running the machine to clear excess lubricant from the raceway of the loop-taker. It will also be noted that the 5 lubricant is not only automatically supplied when the machine is brought into operation, but that the delivery of the lubricant to the shaft-bore is controlled to vary with speed requirements and to obviate excess lubrication of the loop-taker 10 raceway when the machine is in operation.

The work is intermittently advanced by a feed-dog 63, operating through the usual throat-plate 64 and opposed by the usual vertically yielding presser-foot 65. The feed-dog 63 is carried 15 by a feed-bar 66, of which one end is pivotally connected to rocker-arms 67 of a feed-advance rock-shaft 68. The other end of the feed-bar 66 is forked to embrace a stud 69 carried by a crank-arm 70 of a feed-lift rock-shaft 71. 20 The feed-advance rock-shaft 68 is journaled at its opposite ends upon pintles 72 suitably secured in bearing lugs 73 depending from the cloth-plate 1. The rock-shaft 68 carries a crank-arm 74, to which is pivotally connected one end 25 of a pitman 75. At its opposite end, the pitman 75 has a split strap 76 embracing an adjustable eccentric 77 which corresponds substantially with that disclosed in the pending U. S. patent application of W. Myers, Serial No. 74,615, filed Apr. 30, 1936. In the present case, the eccentric 77 is adjustably carried by the lower actuating 30 shaft 34.

The feed-lift rock-shaft 71 is also journaled upon pintles 78 suitably secured in bearing-lugs 35 79 depending from the bed-plate 1. The rock-shaft 71 has another crank-arm 80 operatively connected to a pitman 81 having a strap 82 embracing a feed-lift eccentric 83 which is also carried by the actuating shaft 34.

40 Having thus set forth and nature of the invention, what I claim herein is:

1. In a sewing machine, a rotary loop-taker having a thread-carrier raceway, a casing providing a lubricant-supply chamber, a rotary shaft provided with a longitudinal bore connected with said raceway and terminating in said chamber above the level of the lubricant-supply therein, and means disposed within said chamber and effective during the operation of the machine for directing lubricant into said shaft-bore.

2. In a sewing machine, a rotary loop-taker having a thread-carrier raceway, a rotary shaft carrying said loop-taker and provided with a longitudinal bore connected with said raceway, a casing providing a lubricant-supply chamber housing one end of said shaft above the level of the lubricant-supply in said chamber, and lubricant-directing means disposed within said chamber and extending into the bore of said shaft.

60 3. In a sewing machine, a rotary loop-taker having a thread-carrier raceway, means including a conduit coaxial with said loop-taker for directing lubricant to said raceway, a casing providing a lubricant-supply chamber housing one 65 end of said conduit above the level of the lubricant-supply in said chamber, and means automatically rendered effective upon operation of the machine for directing lubricant from said chamber into said conduit endwise thereof.

70 4. In a sewing machine, a rotary loop-taker having a thread-carrier raceway, a casing providing a lubricant-supply chamber, a rotary shaft provided with a longitudinal bore terminating in said chamber and connected with said raceway, and lubricant-agitating means disposed within

said chamber and automatically rendered effective upon operation of the machine for supplying lubricant to said shaft-bore.

5 5. In a sewing machine, a lubricant-conducting member having a longitudinal bore, a casing housing one end of said member and providing a lubricant-chamber, lubricant-agitating means disposed within said chamber and rendered effective upon operation of the machine, and means for directing particles of the agitated 10 lubricant into the bore of said member.

6. In a sewing machine, a rotary loop-taker having a thread-carrier raceway, a rotary shaft carrying said loop-taker, a lubricant-supply reservoir and means including loop-taker shaft 15 driving devices disposed within said reservoir for supplying lubricant to said raceway.

7. In a sewing machine, a rotary loop-taker body having a thread-carrier raceway, a rotary loop-taker shaft provided with a longitudinal 20 bore connected with said raceway, a casing providing a lubricant-chamber, said bore terminating in said chamber means for agitating lubricant within said chamber including a driving element disposed within said lubricant-chamber for 25 rotating said shaft, and means for directing particles of the agitated lubricant into said shaft-bore.

8. In a sewing machine, a rotary loop-taker having a thread-carrier raceway, a rotary shaft 30 provided with a longitudinal lubricant-conducting bore connected with said raceway, a casing providing a lubricant chamber, a rotary actuating shaft, lubricant-impelling means within said casing comprising intermeshing gears carried by 35 said shafts, and means for directing the impelled lubricant into said shaft-bore.

9. In a sewing machine, a rotary loop-taker body having a thread-carrier raceway, a rotary shaft carrying said loop-taker and having a longitudinal bore connected with said raceway, a casing housing one end of said shaft and providing a lubricant-chamber, a rotary actuating shaft, intermeshing gears carried by said shafts within 40 said casing, a baffle-member disposed to intercept particles of the lubricant agitated upon rotation of said actuating shaft, and means for directing lubricant from said baffle-member into said shaft-bore.

10. In a sewing machine, a rotary loop-taker 50 having a thread-carrier raceway, a casing providing a chamber designed to contain a limited supply of lubricant, lubricant-conducting means connected with said raceway and disposed in said chamber above the level of the lubricant supply 55 when the chamber is filled to capacity, and means rendered effective upon operation of the machine for supplying lubricant in said chamber to said conducting means.

11. In a sewing machine, a rotary loop-taker 60 having a thread-carrier raceway, a casing providing a lubricant-chamber and having an outlet port limiting the supply of lubricant within said chamber, means extending into said chamber above the level of the lubricant-supply therein 65 for conducting lubricant from said chamber to said raceway, and means in said chamber automatically rendered effective upon operation of the machine for supplying lubricant to said conducting means.

70 12. In a sewing machine having a cloth-plate, a rotary loop-taker disposed below said cloth-plate and having a thread-carrier raceway, a rotary loop-taker carrying shaft provided with a longitudinal bore connected with said raceway, a 75

- casing providing a lubricant-chamber below said cloth-plate and housing one end of said shaft, means for supplying lubricant to said chamber from above the cloth-plate, said chamber having an outlet port limiting the supply of lubricant within said chamber to a level below said shaft, and means within said chamber rendered effective upon operation of the machine for conducting said lubricant into said shaft-bore.
10. 13. In a sewing machine, a rotary loop-taker having a thread-case raceway, a rotary shaft provided with a longitudinal bore connected with said raceway, a lubricant-supply reservoir, the bore of said shaft terminating in said reservoir above the level of the lubricant-supply therein, a lubricant-impelling member within said reservoir, means for intercepting lubricant impelled by said member, and lubricant-conducting connections provided with excess-lubricant diverting means between the lubricant-intercepting means and said shaft-bore.
15. 14. In a sewing machine, a rotary loop-taker having a thread-carrier raceway, conduit means for directing lubricant to said raceway, a casing providing a lubricant-supply chamber, means for agitating a supply of lubricant within said chamber upon operation of the machine, means including a baffle-member disposed in said chamber to intercept particles of the agitated lubricant, and means within said chamber for delivering lubricant intercepted by said baffle-member to said conduit means.
20. 15. In a sewing machine, a rotary loop-taker having a thread-case raceway, a lubricant-supply reservoir, lubricant-impelling means disposed in said reservoir, a baffle-member disposed in said chamber to intercept lubricant impelled by said means, a member provided within said reservoir and below said baffle-member with a duct disposed to receive lubricant intercepted by said baffle-member, and means for directing lubricant from said duct to said raceway.
25. 16. In a sewing machine, a lubricant-chamber casing having a side wall provided with a substantially vertical filling-aperture and with a slot connecting said filling-aperture with the chamber of said casing adjacent the bottom wall thereof, said side wall having an overflow port extending outwardly from said filling-aperture above the level of said bottom wall, and a rotary lubricant-impeller disposed within said casing with its axis of rotation transverse to said side wall.
30. 17. In a sewing machine, a lubricant-reservoir, a rotary shaft longitudinally provided with a lubricant-conducting bore and having one end terminating within said reservoir, means within said reservoir including a stationary lubricant-conductor extending into said shaft-bore endwise thereof for supplying lubricant to said shaft-bore, and lubricant-delivering means connected with said shaft-bore.
35. 18. In a sewing machine, a rotary loop-taker having a thread-case raceway, a lubricant-supply reservoir, a rotary loop-taker carrying shaft provided with a longitudinal bore connected with said raceway and terminating in said reservoir, lubricant-impelling means disposed in said reservoir, and a stationary lubricant-duct connected with said bore and disposed within said reservoir to receive lubricant agitated by said impelling means.
40. 19. In a sewing machine, a rotary loop-taker having a thread-carrier raceway, a casing providing a lubricant-chamber, lubricant-impell-
- ing means disposed within said chamber for agitating lubricant during the operation of the machine, and conducting means disposed in said chamber to intercept particles of the agitated lubricant and to deliver said lubricant to said raceway, said conducting means being provided with means automatically effective upon stopping of the machine for interrupting further delivery of lubricant.
45. 20. In a sewing machine, a rotary loop-taker having a thread-carrier raceway, a casing providing a lubricant-chamber, lubricant-impelling means disposed in said chamber for agitating lubricant during the operation of the machine, a rotary loop-taker carrying shaft having a longitudinal bore terminating in said lubricant-chamber and connected with said raceway, and means within said chamber for conducting particles of the agitated lubricant into said shaft-bore, said means including an excess-lubricant controlling device.
50. 21. In a sewing machine, a rotary loop-taker having a thread-carrier raceway, a casing providing a lubricant-chamber, lubricant impelling means disposed in said chamber for agitating lubricant during the operation of the machine, a rotary loop-taker carrying shaft having a longitudinal bore terminating in said lubricant-chamber and connected with said raceway, means within said chamber for intercepting particles of the lubricant agitated by said impelling means, and excess-lubricant by-passing connections within said chamber for delivering the lubricant to said shaft-bore.
55. 22. In a sewing machine having a frame including a work-supporting bed-plate, a rotary loop-taker disposed below said bed-plate and provided with a thread-carrier raceway, a work-advancing feed-dog, a casing below said bed-plate providing a lubricant-chamber, substantially parallel rotary loop-taker and feed-actuating shafts journaled below said bed-plate and extending into said lubricant-chamber, said loop-taker actuating shaft performing a plurality of rotations for each rotation of said feed-shaft, a lubricant-impelling member carried by said feed-shaft within said chamber, means for actuating said feed-dog from said feed-shaft, and means for conducting lubricant agitated by said lubricant-impelling member to said loop-taker raceway.
60. 23. In a sewing machine, a rotary loop-taker having a thread-carrier raceway, a lubricant-supply reservoir, a rotary loop-taker carrying shaft extending into said reservoir and having a longitudinal bore connected with said raceway, a rotary actuating shaft, a lubricant-impelling member carried by said actuating shaft within said reservoir, and means for conducting lubricant agitated by said impelling member into said shaft-bore.
65. 24. In a sewing machine, a rotary loop-taker having a thread-carrier raceway, a lubricant-supply reservoir, a rotary loop-taker carrying shaft extending into said reservoir and having a longitudinal bore connected with said raceway, and means for delivering lubricant to the loop-taker shaft bore including, a lubricant-impelling member disposed within said reservoir and rotatable at one half the speed of rotation of said loop-taker carrying shaft, and means for rotating said member.

SYDNEY ZONIS.
